UNITED STATES PATENT OFFICE.

JOHN PORTER GOLDEN, OF COLUMBUS, GEORGIA, ASSIGNOR TO GOLDEN'S FOUNDRY & MACHINE COMPANY, OF COLUMBUS, GEORGIA.

CANE MILL.

Application filed November 16, 1922. Serial No. 601,368.

To all whom it may concern:

Be it known that I, JOHN P. GOLDEN, a citizen of the United States, and a resident of Columbus, in the county of Muscogee and 5 State of Georgia, have invented certain new and useful Improvements in Cane Mills; and I do hereby declare the following to be a full, clear, and exact description of the invention, such as will enable others skilled 10 in the art to which it appertains to make and use the same.

This invention relates to improvements in cane mills and more particularly to improved guide-knife means for three roll 15 mills.

One object of the invention is to provide a guide-knife construction which shall embody two guide-knife portions adapted to be co-operable with the rolls and which 20 shall be capable of use one at a time so that if one of said guide-knife portions shall have become worn the other (previously idle knife portions) can be brought into active 25 relation to the rolls by reversing the position of the guide-knife structure.

A further object is to provide a guide-knife structure for cane mills which shall be substantial,—providing wide bearing 30 portions against the smaller rollers,—and capable of being easily and accurately adjusted to permit the cane to be fed in one or the other direction through the mill.

A further object is to provide a guide-knife structure for cane mills which will 35 operate to prevent the cane from getting past the flanges of the large roll to the gearing above or dropping to the bottom of the mill.

A further object is to provide simple and 40 efficient means for adjustably supporting a guide-knife structure in position relatively to the rolls to prevent possibility of the cane dropping between the smaller rolls and to insure the proper passage of the cane be- 45 tween the rolls.

With these and other objects in view, the 50 invention consists in certain novel features of construction and combinations of parts as hereinafter set forth and pointed out in the claims.

In the accompanying drawings,—

Figure 1 is a fragmentary plan view showing an embodiment of my invention.

Figure 2 is a fragmentary front view, and

Figure 3 is a similar view partly in section and partly in side elevation.

In the drawings a portion of the frame of a cane mill is represented at 1 and has suitably mounted therein rolls 2, 3 and 4,—the roll 2 being considerably larger than 50 the rolls 3 and 4 and is provided at its respective ends with flanges 5, between which the rolls 3 and 4 project so as to be co-operable with the peripheral face of the roll 2 in a manner to crush the cane represented 55 at 6 as it passes, first between the rolls 2 and 3 and then between the rolls 2 and 4. I have represented the roll 3 as being disposed a short distance from the peripheral face of the roll 2 and between these rolls, 60 the cane first passes but the roll 4 is shown in close proximity to the roll 2 so that as the cane passes between said rolls 2 and 4 it will be completely crushed, leaving nothing but the pulp or bagasse which will be 65 discharged from the mill in any approved manner.

My improved guide-knife structure is represented at 7 and is disposed between the rolls 3 and 4,—said guide-knife structure being suspended by means of a rod 8 from the casing. The rod 8 is threaded through one end of the structure 7 so as to be adjustably connected therewith and the other end of said rod passes through an 80 elongated slot 9 in the frame-work so that the structure 7 may be adjusted relatively to the rolls and said rod is provided at its free upper ends with a head 10, between 85 which and the framework a disk 11 may be disposed. For the purpose of adjusting the structure 7 relatively to the rolls and holding it at the desired adjustment to insure close contact with the feeding roll, an 90 adjusting rod 12 is employed. This rod has a threaded portion 13 to pass through a threaded hole 14 in the structure 7 and the other end portion of said rod is threaded as at 15 and passes through a slot or opening 16 in the frame-work and receives a 95 thumb nut 17, between which latter and the framework a disk 18 may be disposed. The structure 7 is reversible in two directions at right angles to each other as more 100 particularly hereinafter explained and said structure is therefore provided with two threaded openings 14 for the accommodation of the adjusting rod 12 and it is like-

wise provided at its respective ends with threaded openings 8^a for the accommodation of the suspending rod 8.

The guide-knife structure 7 is made in the form of a frame having head portions 19, one or the other of which will be so disposed between the rolls 3 and 4 and in proximity to the roll 2 as to guide the cane from roll 3 to roll 4 and prevent it from getting between these rolls. The guide-knife frame structure provides two pairs of wide bearing faces 20—21, the faces 20 being adapted in the arrangement shown in Figure 1 to engage the periphery of the roll 3 and the faces 21 being arranged to engage the periphery of the roll 4. To provide such extended bearing faces for the guide-knife structure, requires considerable metal and this insures the longevity of the device. The guide-knife structure is provided at its respective ends with flanges or projections 22 (preferably having curved or beveled inner faces) and these flanges or projections enter between the flanges 5 of the large roll 2 so as to feed the cane in directions toward the center of the periphery of the rolls and prevent the cane from escaping beyond one of said flanges 5 to the gearing above or from dropping past the other flange 5 to the bottom of the mill.

With my improved double guide-knife structure, the same can be readily reversed end for end when the active portions at one end of said structure become worn and by reversing the guide-knife structure axially as viewed in Figure 3, said structure can be adapted to permit the cane to be fed through the mill in a direction opposite to that indicated in Figure 1,—it being understood that in such case the positions of the rolls 3 and 4 will be changed so that the roll 3 will be disposed in close proximity to the

roll 2 and the roll 4 spaced from said roll 2 in substantially the position which is represented in Figure 1 by the roll 3.

45

Having fully described my invention what I claim as new and desire to secure by Letters-Patent, is:

1. A reversible guide-knife structure for cane mills having two pairs of roll engaging faces adapted for interchangeable use.

2. A reversible guide-knife structure for cane mills having opposite heads providing, interchangeably, roll engaging portions and means whereby said structure may be reversible in a cane mill.

3. In a cane mill, the combination with framework and three rolls, one of said rolls having flanges adjacent its ends, of a reversible guide-knife structure having opposite heads providing, interchangeably roll engaging portions, disposed between two of said rolls and having flanges entering between the flanges of the other roll, and means for adjustably supporting said guide-knife structure.

4. In a cane mill, the combination with framework and three rolls, of a reversible guide-knife structure having opposite heads providing, interchangeably, roll engaging portions disposed between two of said rolls, means for adjustably suspending said guide-knife structure from the framework, and means for adjusting said guide-knife structure relatively to the roll or rolls with which it cooperates.

In testimony whereof, I have signed this specification in the presence of two subscribing witnesses.

JOHN PORTER GOLDEN.
